(57) **CLAIM**

The ornamental design for a plasma surgical device distal tip, as shown and described.

DESCRIPTION

FIG. 1 is a perspective view of a plasma surgical device distal tip, showing our new design;

FIG. 2 is a perspective view thereof, from an alternate angle;

FIG. 3 is a top elevation view thereof, parallel with a distal end surface of the distal tip;

FIG. 4 is a bottom elevation view thereof, parallel with a distal end surface of the distal tip;

FIG. 5 is a right side elevation view thereof;

FIG. 6 is a bottom view thereof, from an alternate angle;

FIG. 7 is a bottom elevation view thereof, from another alternate angle;

FIG. 8 is an enlarged front elevation view thereof;

FIG. 9 is a perspective view of another embodiment of a plasma surgical device distal tip, in accordance with this disclosure;

FIG. 10 is a perspective view of the embodiment shown in FIG. 9, from an alternate angle;

FIG. 11 is a top elevation view thereof, parallel with a distal end surface of the distal tip;

FIG. 12 is a bottom elevation view thereof, parallel with a distal end surface of the distal tip;

FIG. 13 is a right side elevation view thereof;

FIG. 14 is a bottom elevation view thereof, from an alternate angle;

FIG. 15 is a bottom elevation view thereof, from another alternate angle; and,

FIG. 16 is an enlarged front elevation view thereof.

The portion of the plasma surgery device distal tip depicted in broken lines form no part of the claimed design. The left side elevation view has been omitted as it is a mirror image of the right elevation view presented.
